DESIGN FOR A GARMENT SUPPORTING HOOK

Eugene J. Lux, New York, N. Y., assignor to
Columbia Protekosit Co., Inc., Carlstadt,
N. J., a corporation of New Jersey

Application July 25, 1939, Serial No. 86,229

Term of patent 7 years

To all whom it may concern:

Be it known that I, Eugene J. Lux, a citizen of the United States and resident of New York city (Borough of Manhattan), in the county and State of New York, have invented a new, original, and ornamental Design for a Garment Supporting Hook, of which the following is a specification, reference being had to the accompanying drawing, forming a part thereof, and of which Figure 1 is a view of a garment supporting hook in side elevation; Fig. 2 is a view thereof in front

elevation; Fig. 3 is a top plan view thereof; and Figs. 4, 5, 6, and 7 are sectional views thereof respectively on the lines 4—4, 5—5, 6—6, and 7—7 of Fig. 1.

The dominant feature of the design consists in the garment supporting hook having the generally S-shape, substantially as shown.

I claim:

The ornamental design for a garment supporting hook, substantially as shown and described.

EUGENE J. LUX.
